CLAIM

We claim the ornamental design for a showerhead with dual oscillating massage, as shown and described.

DESCRIPTION

FIG. 1 is a left, front isometric view of a showerhead with dual oscillating massage.

FIG. 2 is a right, front isometric view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged fragmentary view thereof taken along detail line 9-9 of FIG. 2; and,

FIG. 10 is an enlarged fragmentary view thereof taken along detail line 10-10 of FIG. 3.

The broken lines illustrate portions of the showerhead with dual oscillating massage that form no part of the claimed design.
